[57] CLAIM

The ornamental design for a conversion device, as shown and described.

DESCRIPTION

FIG. 1 is a front elevational view of a conversion device showing my new design;

FIG. 2 is a side elevational view of the conversion device;

FIG. 3 is a top plan view of the conversion device;
 FIG. 4 is a rear elevational view of the conversion device;

FIG. 5 is a front elevational view of the conversion device showing the insert extended in the opposite direction to that of FIG. 1;

FIG. 6 is a front elevational view of the conversion device with the insert in a nonextended position.

HOW TO USE THE CONVERSION TABLE

THE FOLLOWING STEPS SHOULD BE TAKEN
TO CONVERT ONE UNIT TO ANOTHER.

1. LOCATE UNIT OF MEASURE TO BE CONVERTED
2. PULL INSERT TILL NUMBER ONE (1) APPEARS
3. READ HORIZONTALLY FOR EQUIVALENTS
4. MULTIPLY THE EQUIVALENT WITH THE
NUMBER YOU WANT TO CONVERT.

EXAMPLE: (WEIGHT MEASURE)

IF YOU WANT TO FIND THE EQUIVALENT OF ONE (1)
POUND (lb), LOCATE THE WORD "WEIGHT" ON THE
FACE OF THIS TABLE, PULL OUT INSERT TILL
NUMBER ONE (1) UNDER POUND (lb) APPEARS.
READ ITS EQUIVALENTS HORIZONTALLY.

ONE (1) POUND (lb) IS EQUAL THE FOLLOWING:

2267.96 carat   7000 gram(s)

453.592 mg.

16 oz.

0.00045 long ton

0.45359 kg.

0.0005 short ton

0.00045 ton

MULTIPLY THE ABOVE EQUIVALENTS WITH THE
NUMBER YOU WANT TO CONVERT TO GET
THE ANSWER.
